UNITED STATES PATENT OFFICE.

JOHN EINSFIELD, OF ONEIDA, NEW YORK.

DESIGN FOR A BURIAL-CASKET.

SPECIFICATION forming part of Design No. 12,286, dated May 31, 1881.

Application filed April 13, 1881. Term of patent 7 years.

To all whom it may concern:

Be it known that I, JOHN EINSFIELD, of Oneida, in the county of Madison, in the State of New York, have invented new and useful 5 Improvements in Design for Burial-Caskets, of which the following, taken in connection with the accompanying drawing, is a full, clear, and exact description.

The nature of my design will be readily comprehended by referring to the accompanying drawing, which represents a side view of a burial-casket ornamented in accordance with my design.

The exterior of the vertical sides of the casket 15 is covered smoothly with a facing of cloth, as indicated by the letter A.

From a suitable molding, m, usually extended around the casket near the upper edge of the vertical sides, are suspended a series of 20 smooth draperies, B B, in the form of long flaps or curtains of cloth hung from the molding m aforesaid. The loose edges of the draperies are trimmed with a puffed band, a, and fringe b pendent therefrom. The ends of the 25 respective draperies B are cut bias, and made to nearly or quite meet at their upper corners. At the junction of said corners are arranged rosettes C, and from the latter are suspended tassels D.

30 E represents a cord suspended from one rosette to the other, and hung over the draperies B. An ornamental slide, s, applied to the said cord adds to the embellishment of the casket.

What I claim is—

1. The design for the embellishment of burial-caskets, consisting of smooth flaps B B, hung on the exterior of the casket and suitably trimmed at their edges, substantially as shown. 35

2. The within-described ornamentation of burial-caskets, consisting in the combination, 40 with the cloth-faced sides A, of the pendent smooth draperies B B, and the rosettes C at the junction of said draperies, substantially as shown.

3. As an ornamentation of burial-caskets, 45 the combination, with the cloth-faced sides A, of the pendent smooth draperies B B, trimmed at their edges with a puffed band, a, and fringe b, the rosettes C at the junction of said draperies, and the tassels D pendent from said 50 rosettes, substantially as described and shown.

In testimony whereof I have signed my name and affixed my seal, in the presence of two attesting witnesses, at Syracuse, in the county of Onondaga, in the State of New York, this 55 18th day of March, 1881.
